Garrettson Smith and Henry Brown, of Philadelphia, Pa.

Assignors to

J. G. Abbott and A. Lawrence of Phila. aforesaid,
Letters Patent No 1029. Dated July 20. 1858.

The schedule referred to in these Letters Patent and making part of the same.

To all whom it may concern:

Be it known, that we Garrettson Smith & Henry Brown, of the City and County of Philadelphia, and State of Pennsylvania, have produced a new original Design for Franklin Radiator Stove, and we do hereby declare that the following is a full, clear and exact description of the same, reference being

had to the annexed drawing forming part of this specification, in which

Figure 1. is a front view of the stove.

Figure 2. is a top view.

Figure 3. is a view of base plate.

Figure 4. is a view showing fender piece.

Figure 5. is a view of front foot.

Figure 6. is a view of back foot.

Similar characters of reference denote the same part.

Upon the front plate A. are the feed doors B. and ash pit doors C. sliding behind the pieces D. and E.

The piece D. which surmounts doors B. is ornamented with foliage a. flowers b. and scroll c. arranged as shown in fig. 1. the piece E. is embellished with foliage d. and figure e. configured as shown in fig. 1.

The doors B. are ornamented with the entwined vine and foliage f. g. arranged as shown in the drawing; and the doors C. are ornamented with the entwined vine h. foliage i. and flowers j. arranged and having the configuration shown in fig. 1.

On each side of the body of the stove are ornamental pieces P. made up of scrolls, and foliage arranged as shown in the drawing.

The edge of the top plate F. is ornamented with scrolls k. and foliage l. as shown in fig. 1.

The upper surface of the top plate F. is ornamented in bas. relief by scrolls m. foliage n. and figures p. and q. the whole having the design, configuration and arrangement shown in fig. 2.

The base plate G. is of the form shown in fig. 3. and bears sweeping foliage r. and s. and figures t. in bas. relief. The draw hole cover I. is ornamented with figures u. and foliage v. The plate G. has the inscription "Patented 1858. Abbot & Lawrence Philadelphia" in raised Capitals and numerals.

The fender piece H. is ornamented as shown in the drawing by foliage a' b'.

The front foot J. is ornamented by scrolls c'. and foliage d' as shown in fig. 5.

The back foot is of the form and bears the ornaments set forth in fig. 6.

We claim the design, configuration and arrangement of the several
